HARNESS MOTION FOR LOOMS

William G. Trautvetter, Paterson, N. J.

Application June 15, 1938, Serial No. 213,776

6 Claims. (Cl. 139—55)

This invention relates to an improved harness motion for looms and has for an object to provide a construction which is designed to give the heddles a smooth and uniform action.

Another object of the invention is to provide a harness motion for looms wherein a dwell may be provided during the time the shed is accommodating the shuttle.

A further and more specific object of the invention is to provide a harness motion for looms which will cause the heddles to move smoothly and uniformly and which may be adjusted to vary the dwell of the shed so that the speed of the loom may be increased without putting any undesirable tension on the warp yarn.

In the accompanying drawings—

Fig. 1 is a side view of part of a loom with a harness motion disclosing an embodiment of the invention applied thereto;

Fig. 2 is a front view of the structure shown in Fig. 1;

Fig. 3 is an enlarged view of the control mechanism of the harness motion shown in Figs. 1 and 2, said view being a section through Fig. 4 approximately on the line 3—3;

Fig. 4 is an edge view of the structure shown in Fig. 3;

Fig. 5 is a view similar to Fig. 3 but showing a modified form of the invention.

Referring to the accompanying drawings by numerals, 1 indicates the frame of a loom which may be of any desired construction and provided with any desired number of heddles 2 which also may be of any desired structure. As is well known the heddles 2 may be lowered under the action of gravity through the use of weights or under the action of springs. The particular construction of heddles and means for lowering the same form no part of the present invention but the means for raising the heddles and releasing the same does disclose the invention as illustrated in the accompanying drawings. In Fig. 2 it will be seen that there are provided cables 3 and 4 which are adapted to be passed over suitable pulleys 5 and 6 connected to the upper part of the heddles 2 so that when these cables are pulled the heddles will be raised and when these cables are released the heddles will be lowered. It will of course be understood that the device may be connected with one or any desired number of heddles without departing from the spirit of the invention though ordinarily the device is connected with two heddles to form an ordinary shed during the functioning of the loom. It will of course be understood that when one heddle is up

the other heddle is down and the shed is formed whereby the shuttle of the loom may readily pass for laying a warp yarn.

The cables or straps 3 and 4 are connected to a step pulley 6, as shown in Fig. 1, which pulley is rigidly secured to a shaft 7, rotatably mounted in suitable journal members 8 and 9 carried by the frame. A crank 10 is keyed or otherwise rigidly secured to shaft 7 and as this crank swings upwardly and downwardly the step pulley 6 will be rocked in one direction or in the opposite direction. The crank 10 is provided with a slot 11 through which a pin 12 extends. This pin is adapted to be locked at any desired point along the slot 11 by any desired means, as for instance by having the pin formed with a shoulder resting against the crank 10 and a nut 13 screwed on to the loose end for clamping the pin rigidly in place. A shackle 14 is rotatably mounted on the shaft 12 and a rod 15 is connected therewith through a bifurcated end 16 which straddles part of the shackle 14 and which accommodates the journal pin 17 extending through the arms of the bifurcated end 16 and through part of the shackle. This gives, in a certain sense, a universal connection to the parts whereby as the shaft or rod 15 reciprocates crank 10 will be rocked and the heddle 2 will be raised and lowered. The rod 15 is connected to the crank 18 through the bifurcated end member 19 in the same way that the rod 15 is connected with the crank 10. It will therefore be seen that the universal connection permits a desirable swinging motion in planes at right angles to each other while the pin 20 may be adjusted longitudinally of a slot 21. The driving crank 18 is rotatably mounted on a stud shaft 22 which is secured by set screws or otherwise to the tubular extension 22' of the frame 24. Directly below the stud shaft 22 there is provided a drive shaft 23 which is driven by an electric motor or any other suitable source of power which operates the loom as it functions. It will therefore be evident that the shaft 23 must move in proper time for the movement of the mechanism for throwing the shuttles. The supporting frame 24 is secured by various bolts 25, 26 and 27 to the frame 1 and coacts with an auxiliary frame 28 for supporting and holding in position certain parts hereinafter fully described. The frame 28, as shown in Fig. 3, has an almost L-shaped formation with one end surrounding the shaft 23, with the center accommodating the bolt 29 and with the opposite end accommodating the bolt 30. It will be understood that the shaft 23 freely ro-

tates in the end of the frame 28 but that a power crank 31 is keyed or otherwise rigidly secured to the shaft. A notched wheel 32, commonly known as a star wheel, is rotatably mounted on the shaft 29 and actuates a large gear wheel 33. This gear wheel carries a number of pins 34 which slidably fit into apertures 35 in the star wheel 32. Gear wheel 33 continually meshes with a pinion or small gear wheel 36 which rotates on the stud shaft 22. This shaft is rigidly clamped to the tubular extensions 22' of plate 24.

The power crank 31 is provided with a wheel 37 rotatably mounted upon a pin 38, which pin 15 is secured in any desired manner to the crank 31. This wheel is adapted to readily move into any of the notches 39 formed in the star wheel 32 so as to move the star wheel a desired distance. A retaining or holding disk 40 is carried 20 by the crank 31 and is adapted to move into the arc-shaped depressions 41 for holding the star wheel 32 stationary after the roller or wheel 37 has moved out of a particular notch 39. As shown in the accompanying drawings the shaft 25 23 will rotate six times to one rotation of the star wheel 32 and the gear wheel 33. If desired, the star wheel 32 could be made with more or less notches and, consequently, the ratio of rotation of the parts just mentioned could be varied. The movement of the star wheel 32 causes 30 the rotation of pinion 36 and driving crank 18 sufficiently to change the shed and then hold the shed stationary during the time the star wheel 32 is stationary. The parts could be so proportioned that the dwell would be 240° and the movement of the parts 120°. This would give 35 an exceptionally long dwell for accommodating the shuttle and is desirable where the yarn is rather delicate. Also by giving an exceptionally long dwell the shed need not be as great as where there is no dwell at all. By varying the proportions of the parts the dwell could be varied, for instance from 240° down to 120°, or for an even less time, though ordinarily the dwell 40 would be 120° or more in order to take care of the shuttle when the loom is running at comparatively high speed.

By providing the parts as just described the movements of the heddles are smooth and uniform and not jerky. By reason of this fact the yarn will not be readily broken even though it may be delicate or some particular end may be weakened. The smoothness of the starting and stopping of the heddles, therefore, will result in 50 a better piece of woven cloth as well as the resulting production of a greater yardage of cloth as the stoppage of the loom will be less frequent. During the usual functioning of the device the shaft 23 rotates at a uniform speed and 55 in proportion to the action of the shuttle so that the sheds will be made at the proper time. However, when the loom is not in use the shaft 23 may be rotated by the hand wheel 42 in order to set the heddles or the various parts in the 60 desired way.

In Fig. 5 the same inventive concept is presented but the specific structure for the transmission of power to the driving crank 18 is different. Referring particularly to this figure it 70 will be seen that the large gear wheel 33 is driven through the action of a ratchet wheel 43. This ratchet wheel is preferably rigidly secured to a shaft 44 and the gear wheel 33 in this form of the invention is also secured to the same shaft, 75 which shaft is rotatably supported by a support-

ing plate 24' and a frame 28'. A link 45 is rockably mounted on the shaft 44 and at 46 is pivotally connected with a second link 47 which in turn is pivotally connected at 48 to a power crank 31'. The crank 31' is identical with crank 31 shown in Fig. 1, and by reason of shaft 23 continually rotates during the operation of the loom. By means of the construction just described the link 45 swings upwardly and downwardly. A pawl 49 is pivotally mounted at 50 on link 45 and is resiliently held by a retractile spring 51 so that the pawl will continually engage the ratchet wheel 43. It will therefore be noted that as the shaft 23 rotates pawl 49 moves upwardly and downwardly and on the downward stroke will move the ratchet wheel 43, gear wheel 33, and associated parts, while on the upward stroke these members remain at rest and, consequently, there is a dwell in the shed.

I claim:

1. A harness motion for a loom having heddles and a constantly rotating shaft, comprising mechanism for raising and lowering said heddles to form a shed, said mechanism including a reciprocating member, and means actuated by 25 said shaft for causing said reciprocating member to have a stationary dwell after forming each shed, said means including, a pinion, a large gear continually meshing with the pinion, and means intermittently moving said large gear a 30 certain number of times for each rotation of the large gear, said pinion being so proportioned to said large gear that it will move one-half a revolution upon each intermittent movement of said large gear.

2. A harness motion for looms including a reciprocating structure, a rotatable member for causing said reciprocating structure to function, a pinion connected with said rotatable member for causing the rotatable member to function, a 40 notched member connected with said gear wheel for causing the gear wheel to function, and a power driven member intermittently engaging said notched member in the respective notches thereof in succession for intermittently causing 45 said notched member to function.

3. A harness motion for looms including a reciprocating structure, a rotatable member for moving said reciprocating structure, a pinion for rotating said rotatable member, a gear wheel 50 continually in mesh with said pinion for rotating said pinion, a star wheel connected with said gear wheel, power driven means coaxing with said star wheel for causing the star wheel to function and thereby cause said gear wheel to 55 intermittently rotate and operate the heddles of the loom and provide a stationary dwell while the star wheel remains stationary and a quick changing of the shed while the star wheel is moving.

4. A harness motion for looms including a reciprocating rod, a crank for moving said rod, a pinion for operating said crank, a gear wheel continually meshing with said pinion and means for intermittently moving said gear wheel, said 65 means including a star wheel removably secured to said gear wheel and a power driven member actuated by the power operating the loom so that the star wheel will function in time with the remaining parts of the loom and will cause 70 a quick forming of the shed and a stationary dwell in the shed while the star wheel is being held stationary.

5. A harness for looms having a plurality of heddles and a constantly rotating shaft, com- 75

prising mechanism for raising and lowering said heddles to form sheds, said mechanism including a reciprocating member for each of said heddles, a rotatable member for each of said reciprocating members for causing said reciprocating members to function, a gear wheel rigidly connected with said rotatable members, a second gear wheel meshing with the first-mentioned gear wheel, a rotatable structure secured to said second gear wheel for intermittently rotating the same, and means actuated by said constantly rotating shaft for intermittently actuating said rotatable structure whereby the sheds are formed quickly as the second gear wheel moves and are held stationary while the second gear wheel is stationary.

6. A harness motion for looms including a re-

ciprocating rod, a rotatable member for reciprocating said rod, a pinion for rotating said rotatable member, a gear wheel continually meshing with said pinion, a star wheel rigidly secured to said wheel whereby when the star wheel is moved said gear and pinion will be moved, a pair of supporting frames carried by said loom for supporting said pinion, gear and star wheel, and a power-driven member actuating said star wheel actuated by the power operating the loom so that the star wheel will function in time with the remaining parts of the loom and cause a quick forming of the shed and a stationary dwell in the shed while the star wheel is being held stationary.

WILLIAM G. TRAUTVETTER.
